UNITED STATES PATENT OFFICE.

TIMOTHY STEBBINS, OF DAVENPORT, IOWA, ASSIGNOR TO RED JACKET MANUFACTURING COMPANY, OF DAVENPORT, IOWA, A CORPORATION OF IOWA.

PUPPET-VALVE.

No. 833,559.

Specification of Letters Patent.

Patented Oct. 16, 1906.

Application filed August 8, 1905. Serial No. 272,552.

To all whom it may concern:

Be it known that I, TIMOTHY STEBBINS, a citizen of the United States, and a resident of Davenport, in the county of Scott and State 5 of Iowa, have invented certain new and useful Improvements in Puppet-Valves, of which the following is a full, clear, and exact specification.

My invention relates to puppet-valves for 10 pumps; and its object is to provide means for retaining the said valve in operative relation to its seat in such manner that both the valve and said retaining means can be inserted down into the well from above ground and 15 secured in place or removed therefrom for repairs, according as desired; and its object is also to provide a valve which will lift from or drop into its seat without the possibility of binding either in its open or shut position. 20 This I accomplish by the means hereinafter fully described and as particularly pointed out in the claims.

In the drawings, Figure 1 is a vertical section of a coupling in which the valve-seat of 25 the puppet-valve is located, showing my improvements applied thereto. Fig. 2 is a transverse section thereof, taken on dotted line 2 2, Fig. 1. Fig. 3 is a side view of a modified form of valve capable of use in connection with said retaining means. Fig. 4 is 30 a transverse section taken on dotted line 4 4, Fig. 3, looking in the direction of the arrows.

Referring to the drawings, A represents a coupling which connects the sections of the 35 well-pipe a above the puppet-valve in which the lower cylinder of the pump is located and the well-pipe below the same. About its center of length this coupling is provided with an inwardly-projecting flange k, which 40 restricts the bore of the well and has the valve-seat B screwed into the restricted opening made thereby. This valve-seat is cylindrical from its lower to near its upper end b, which latter extends above the flange 45 k and is made thicker, so as to further reduce the valve-opening. The outer circumference of this upwardly-extending portion b is undercut, substantially as shown. The valve engaging this seat B comprises a circular plate 50 c of a diameter sufficient to cover said seat and has its under side faced with leather d or other suitable material. Projecting centrally upward from plate c is a stud e, whose

lower cylindrical portion is smooth and whose upper portion is screw-threaded. This stud 55 e projects up through a suitable central guide opening in the boss C of a spider, which has three or more corresponding equidistant inverted-L-shaped legs D D, the inner edges of which serve as guides for the circumferential 60 edges of the plate c of the valve and, together with the engagement of the guide-opening of the boss of the spider by the stud e thereof, insures the movement of the valve in a vertical plane to and from the valve-seat. The 65 inner surfaces or edges of the legs D are provided with a convexed double bevel forming a kind of foot F, and as said legs are cast of a metal having a certain degree of elasticity when the valve is lowered by some means, 70 such as the lower end of the plunger or a pipe into whose lower extremity it is screwed until it closes the valve-opening, the extremities of the legs snap over the outer inverted beveled edge of the valve-seat and are re- 75 tained thereby sufficiently tight to hold the spider in such position as to confine the valve and guide the reciprocations of the same in the manner hereinbefore described.

In view of the fact that when it is desired 80 to release the valve after it has been inserted in place it is necessary to unscrew the means by which it was lowered from stud e, and it is desirable to prevent the spider from revolving with it I provide the outer circumference 85 of the valve-seat with a stop-lug I, which one of the legs of the spider will engage and prevent further revolution thereof should the friction of the valve have a tendency to turn it.

In Fig. 3 of the drawings I show a modified 90 form of the valve. In this modification the plate f is constructed the same as plate c, hereinbefore referred to, except that it is provided with a central screw-threaded opening G, which extends longitudinally up 95 into its stud g. A rubber packing-ring h is placed against and is secured to the under side of plate f and is secured thereto by a disk H, that has a screw-threaded stud H', which screws up into the screw-threaded 100 central opening G in plate f until said packing-ring is clamped between it and said plate f. Projecting downward from this disk are wings j, which extend in planes at right angles to each other and intersect at a point in 105 alinement with the axis of stud H'. These

wings extend down through the valve and serve as an additional means to direct the movements of the valve.

What I claim as new is—

- 5 1. In a well the combination with a valve-seat having an undercut outer circumference, and a puppet-valve having a vertical stud arising therefrom, of a spider engaged by said stud and having legs that spread over and in-
10 close said valve and are provided with enlarged lower ends that engage the undercut portion of the valve-seat whereby said spider is removably retained in proper position to confine and guide said valve.
- 15 2. In a well the combination with a valve-seat having an undercut outer circumference, and a puppet-valve having a vertical stud arising therefrom, of a spider having a perforated boss engaged by said stud and having
20 legs that spread over and inclose said valve and are provided with enlarged lower ends that engage the undercut portion of the valve-seat whereby said spider is removably retained in proper position to confine and guide
25 said valve.
3. In a well the combination with a valve-seat having an undercut outer circumference, and a puppet-valve having a vertical stud arising therefrom, of a spider engaged by said
30 stud and having legs that spread over and inclose said valve and have their extremities provided with enlargements that interlock with the undercut portion of said valve-seat.
- 35 4. In a well the combination with a valve-seat having an undercut outer circumference, and a puppet-valve having a vertical stud arising therefrom, of a spider having a perforated boss engaged by said stud and having legs that spread over and inclose said valve
40 and have their extremities provided with enlargements that removably interlock with the undercut portion of the valve-seat.
- 45 5. In a well the combination with a valve-seat having an undercut outer circumference, and a puppet-valve having a vertical stud arising therefrom, of a spider engaged by said stud and having elastic legs that spread over and inclose said valve and are provided with enlarged lower ends that engage the under-
50 cut portion of the valve-seat whereby said spider is removably retained in proper position to confine and guide said valve.
6. In a well the combination with a valve-seat having an undercut outer circumference, and a puppet-valve having a vertical stud 55 arising therefrom, of a spider having a perforated boss engaged by said stud and having elastic legs that spread over and inclose said valve and are provided with enlarged lower ends that engage the undercut portion of the valve-seat whereby said spider is removably retained in proper position to confine and guide said valve.
7. In a well the combination with a valve-seat and a puppet-valve having a vertical 60 stud arising therefrom, of a spider engaged by said stud and having legs that spread over and inclose said valve and have the inner edges of their extremities provided with a convexed double bevel and interlock with 70 said valve-seat.
8. In a well the combination with a valve-seat and a puppet-valve having a vertical 75 stud arising therefrom, of a spider having a perforated boss engaged by said stud and having legs that spread over and inclose said valve and have the inner edges of their extremities provided with a convexed double bevel and removably interlock with the
80 valve-seat.
9. In a well the combination with a valve-seat and a puppet-valve having a vertical 85 stud arising therefrom, of a spider engaged by said stud and having elastic legs that spread over and inclose said valve and have the inner edges of their extremities provided with a convexed double bevel and interlock with said valve-seat.
10. In a well the combination with a valve-seat and a puppet-valve having a vertical 90 stud arising therefrom, of a spider having a perforated boss engaged by said stud and having elastic legs that spread over and inclose said valve and have the inner edges of their extremities provided with a convexed 95 double bevel and removably interlock with the valve-seat.

In testimony whereof I have hereunto set my hand this 25th day of July, A. D. 1905.

TIMOTHY STEBBINS.
